UNITED STATES PATENT OFFICE.

MARCO TUDOROV, OF SAN FRANCISCO, CALIFORNIA.

COMBINATION AND KEY PADLOCK.

1,355,084.

Specification of Letters Patent.

Patented Oct. 5, 1920.

Application filed October 14, 1919. Serial No. 330,548.

To all whom it may concern:

Be it known that I, MARCO TUDOROV, citizen of the United States, residing at San Francisco, in the county of San Francisco, State of California, have invented a new and useful Combination and Key Padlock, of which the following is a specification in such full and clear terms as will enable those skilled in the art to construct and 10 use the same.

My invention relates to improvements in combination and key padlocks, and one object of the present invention is to provide means for operating a combination lock by 15 the use of a key.

Another object of the invention is to provide means for operating the combination lock by the key and means whereby the key must be withdrawn from the lock before it 20 can be opened.

Another object of the invention is to provide a simple and strong padlock that will be difficult to unlock without knowing the combination and having a key that fits.

25 Other objects of the invention will appear as the description proceeds.

An embodiment of the invention is shown in the accompanying drawings in which the same reference numeral is applied to the 30 same portion throughout, but I am aware that there may be modifications thereof.

Figure 1 is a perspective view of the padlock with key in position.

Fig. 2 is a longitudinal section of the preferred form of locking mechanism,

Fig. 3 is a section on the line 3-3 in Fig. 2, with the parts shown in Fig. 5 left out for purposes of illustration,

Fig. 4 is a face view of the padlock showing combination dial and keyhole,

Fig. 5 is a detail of parts shown in section in Fig. 2,

Fig. 6 is a longitudinal section of a modified form of locking mechanism,

Fig. 7 is a detail of parts shown in section in Fig. 6,

Fig. 8 is a detail of the revolving cylinder,

Fig. 9 is a perspective view of the tumbler 17, and

Fig. 10 is a perspective view of the member 20.

The numeral 1 indicates the body of the padlock in which a shackle 2 forms the locking member, and has the under-cut portion 5 as shown at 3 and the groove 4 thus forming an overhanging portion 5. This over-

hanging portion 5 will form the locking means, when in contact or is held by the shoulder 6 of the movable dial 7. The dial 7 is free to revolve and has a keyhole 8 made to fit a special key 9 for each lock.

The dial 7 is held in place by the ring 10. This ring can be retained in place by any suitable means, as by riveting in as shown at the edge 11. The dial 7 is provided with a slot 12 in which the latch 13 is pivoted on the dial body at 14. The shape of the latch 13 conforms to the outer surface of the dial body and shoulders 15 prevent the latch 13 from swinging out beyond the cylindrical surface of the dial body 7. The latch is shown with the shoulders 15 in contact with the inner edges of the slot 12 in Figs. 2, 3, and 8.

The latch 13 has a projecting portion 16 which is adapted to swing across the keyhole 8 when the key 9 is withdrawn, thus allowing the latch 13 to drop into the permutation notches; when the key is inserted the latch 13 is held so its outer surface conforms with the surface of the dial body 7 which has the shoulder 6.

When the dial 7 is turned so that the latch 13 registers with the overhanging portion 5 of the shackle 2, and the permutation tumbler 17 is turned so that its notch 18 is in line with the notch 19 in the flange 20, the latch will swing into said notches when the key is withdrawn, thereby allowing the shackle to drop down far enough so that the opposite member of the shackle will be free to swing around as shown by the dotted lines at 2'.

The permutation tumbler 17 is a part of the tubular body 21 and is free to turn in the flange 20 which is stationary. The permutation tumbler 17 and flange 20 are held tightly together by the friction of the cross bar 21', spring 22 and pin 23. The permutation tumbler is turned so that its notch 18 is in line with the notch 19 by turning the key to the right in this instance, until a predetermined number on the dial is in line with a predetermined number on the face. Now the dial is turned back to another predetermined number on the face which brings the latch in line with the notches, and by removing the key, the latch falls in and the shackle is free to drop down.

This action is attained by the rotatably mounted cylinder 24 into which the key projects, by means of a pawl 25 pivoted in the

permutation tumbler 17 with a spring 25' and engaging a notch 26 in the cylinder, so that when turned to the right it turns the permutation tumbler with it, but when 5 turned back, turns freely and leaves the permutation tumbler stationary. But in the back turn, the dial brings the latch in line with the notches.

The mechanism is assembled as follows:

- 10 The shackle 2 is first inserted about as shown in Fig. 2, then the flanged member 20 is assembled, with permutation tumbler 17, member 21, spring 22 and pin 23. This unit as assembled is placed in position from the 15 dial face side and has to be tilted so it will swing under the overhanging projection 5 of the shackle, and is held in the position in Fig. 2 by the dial body 7 and the dial body is held in place so it can turn freely 20 by the ring 10. This ring is preferably riveted in as shown, the complete operation is as follows:

The key 9 is inserted and the dial 7 turned clockwise so the mark on said dial registers 25 with a predetermined mark on the body 1. This turns the permutation tumbler 17 so its notch 18 comes directly over the notch 19 which is in line with the shackle 2. Now 30 the key is turned back counter clockwise so that the said mark on the dial registers with another predetermined mark on the body 1, and as the counter clockwise movement does not move the permutation tumbler, the latch 13 is turned back in line with the notches 35 18 and 19 and the shackle 2 and when the key 9 is removed, the projection 16 swings over the keyhole allowing the latch 13 to drop into the notches 18 and 19, thereby releasing the overhanging portion 5 of the shackle 40 and allowing it to drop as far as the flanged member 20; this position frees the opposite end of the shackle and allows it to swing around as shown at 2', Fig. 4.

When the key is turned counter clockwise 45 a click can be heard when the pawl 25 drops into the notch 26 by the action of the spring 25' this fact can be used to detect tampering with the padlock by turning the dial clockwise to a certain noted position and 50 removing the key, then when the key is inserted and the dial turned counter clockwise the pawl will click at the noted position; if it clicks at some other point, the dial has been turned.

55 The modified form shown in Fig. 6 dis-

penses with the ratchet action by turning the permutation tumbler 17 directly with the key 9 to a predetermined point which brings the notch 18 in line with notch 19 and the shackle 2, and then raising the key and turning the dial body back to a predetermined point and then removing the key so the latch can drop in the said notches and allow the shackle to drop as described above.

What I claim is as follows, but various 65 modifications may be made in the construction shown in the drawings and above particularly described form, within the purview of my invention.

1. A combination and key padlock comprising a body, a slideable shackle with the free ends projecting into said body in a locked position, one of said ends being free from said body in an unlocked position, a rotatable dial with a groove into which a 70 portion of the other of said ends is adapted to slide in a locked position, an opening in said dial communicating with said groove and adapted to be filled by a pivoted latch when in a locked position, a rotatable 75 tumbler adapted to hold said pivoted latch in a locked position, a notch in said tumbler into which the said latch falls in the unlocked position, means for turning said rotatable tumbler in one direction by turning 80 said dial, and means for holding said rotatable tumbler stationary when said dial is turned in the opposite direction.

2. A combination and key padlock comprising a body, a slideable shackle mounted 90 in said body, an overhanging portion of said shackle adapted to slide in a groove in a rotatable dial body, a releasing latch in said groove, a rotatable tumbler with a notch adapted to release said latch when turned to 95 bring said notch in alignment with said releasing latch, a key adapted to slide through said dial body and enter said rotatable tumbler so that when said tumbler is turned to a certain point marked by a character on 100 the face of said dial, the said key can be raised to clear said rotatable tumbler and turn the said dial body back to bring said releasing latch in line with said notch in said tumbler as indicated by a character on 105 the face of said dial.

In testimony whereof I have hereunto set my hand this 2nd day of October, A. D. 1919.

MARKO TUDOROV.
